CHAIN MACHINE

William F. Biedermann, Providence, R. I., assignor to Federal Chain Company, a corporation of Rhode Island

Application November 9, 1936, Serial No. 109,909

10 Claims. (Cl. 59—16)

This invention relates to a chain machine, and has for one of its objects the provision of mechanical means for forming from wire a curbed chain in which each link passes through two or 5 more other links.

Another object of the invention is an arrangement for positively opening up of spaces through previously formed links so as to receive the wire of the link being formed and afford a rapid operation of the machine.

Another object of the invention is the provision of a double, triple or the like curbed chain from a wire having various sectional shapes.

Another object of the invention is the provision 15 of a double curbed chain which is unsoldered and yet each of the ends of the links abut and are in alignment.

With these and other objects in view, the invention consists of certain novel features of construction, as will be more fully described, and particularly pointed out in the appended claims.

In the accompanying drawings:

Fig. 1 is a top plan view of the machine;

Fig. 2 is a sectional view of the mechanism for 25 feeding the wire;

Fig. 3 is a sectional view on line 3—3 of Fig. 2;

Fig. 4 is a sectional view through the ratchet collar of the feeding mechanism;

Fig. 5 is a sectional view of a portion of the 30 ratchet collar on line 5—5 of Fig. 4;

Fig. 6 is a sectional view on line 6—6 of Fig. 2;

Fig. 7 is a sectional view on line 7—7 of Fig. 3, showing the presser foot;

Fig. 8 is a sectional view showing one pair of 35 gripping jaws and mounting mechanism therefor;

Fig. 9 is a sectional view through the parts shown in Fig. 8;

Fig. 10 is a sectional view on line 10—10 of 40 Fig. 9;

Fig. 11 is an enlarged somewhat diagrammatic view showing the feed of the wire from which the links are formed and the relative position of 45 the jaws at one instant of the operation of the machine;

Fig. 12 is a similar view showing the parts in a different position at another instant of operation of the machine;

Fig. 13 is a view similar to Figs. 11 and 12 showing a more advanced relative position of the parts in the operation of the machine;

Fig. 14 is a view similar to Fig. 11 showing additional links of the chain as formed and connected to the part gripped by the jaws;

Fig. 15 is a perspective view of one of the links of the chain;

Fig. 16 is a top plan view showing several links of the chain connected together;

Fig. 17 is a perspective view of a modified form 5 of link opening probe;

Fig. 18 is a view similar to Fig. 17 showing the parts in a different position and engaging a link;

Fig. 19 is a section on line 19—19 of Fig. 17;

Fig. 20 is a perspective view showing the operation of the presser foot;

Fig. 21 is an enlarged somewhat diagrammatic view similar to Fig. 13 but showing a modification of the product formed;

Fig. 22 is a top plan view showing several links 15 of a modified form of chain with respect to Fig. 16.

Heretofore, although it has been known to provide curbed links, or even double curbed link chains, where each link was formed in a separate header, it has never been known to automatically 20 provide a knife-edged chain in curbed form where the wire forming each link was passed through two or more of the links prior to the completion of the link being formed and prior to the severing of the wire from the elongated piece from which 25 it is fed; and in order that this may be done effectively I feed the wire in the form of a corkscrew or a somewhat distorted helix by rotating the same, and I pass the end of the wire so shaped through two or more previous links by providing 30 guides to force or push the formed links to a desired position to receive the wire thus fed. I then sever the wire, complete the link and curb the same by a twisting operation through substantially 35 90°. All this being done automatically without the necessity of hand manipulation of the wire stock or any of the machine parts; and the following is a more detailed description of the present embodiment of this invention illustrating the preferred means by which these advantageous 40 results may be accomplished:

With reference to the drawings, 20 designates the bed of the machine upon which the various parts are mounted. A drive shaft 21 is mounted in bearings 22, 23 and 24 and has a bevel gear 45 25 thereon meshing with bevel gear 26 on the driven cam shaft 27 mounted in bearings 28 and 29 on the bed of the machine. A crank wheel 30 is provided with a crank 31 thereon which is connected to a rack bar 32 slidably mounted in 50 hanger 33 rockably supported by the sleeve 34 which sleeve is rotatably mounted in a bearing block 35 secured to the bed of the machine. This sleeve 34 has a pinion 36 for meshing with the rack 37 on the rack bar 32 to derive motion 55

therefrom. At one end of the sleeve 34 a ratchet collar 38 is secured by set screw 40. Recesses 39 in the face of the collar are deep at one end and extend out substantially flush with the surface of the collar at the other end.

A mandrel 41 extends through the sleeve 34 and has a collar 42 secured by set screw 43 thereon to engage the hanger 33 which is mounted upon the sleeve 34 and prevent movement in one direction. This mandrel 41 is freely rotatable within the sleeve 34. A collar 44 is fixed on this mandrel by set screw 47 provided with spring pressed plungers 45 mounted in recesses 46 in the collar 44. As the ratchet collar 38 is turned in one direction by reason of being turned by the pinion 36, the collar 44 is engaged through these plungers 45 contacting the abutting end of the inclined recess, and is turned in one direction, whereas a movement of the sleeve 34 and collar 38 in the other direction will permit the plungers 45 to slide up upon the inclined recess 39 and will not transmit motion. This collar 44 is also prevented from rotating in one direction by reason of the leaf spring 48 engaging a notch 49 in the collar 44. Thus, the mandrel is intermittently turned in one direction only, through the mechanism just described.

Fixed in the block 35 there is a cylindrical member 50 into which the mandrel extends. This member is grooved in somewhat the manner of a helical path as at 51 with an opening 52 therethrough through which the wire 53 from which the links are to be formed is to be fed. This wire, although it may be of any shape, is here shown as generally triangular in shape or knife-edged with the knife edge outwardly. The mandrel at the end within this helically grooved portion is reduced to provide a blade-like formation 54 which is twisted slightly, as may best be seen in Fig. 2, and is provided with a notch 55 at its end. This blade-like form gives to the links an elongated shape rather than perfectly round, and of course, the shape of the mandrel may be varied for the provision of different shaped links. The shape, however, being out of round causes the wire to be fed forwardly when the mandrel turns in the helically slotted cylinder. An L-shaped arm 56 is secured to the cylindrical member 50 and is provided with a notch 57 in its end to receive the wire as it is fed and guide it between the walls of this notch and the end of the tube 50. This member 56 at its L-shaped end forms one portion of the cutter for severing the wire, as will presently appear.

Two pair of jaws operating one above the other and in a plane substantially parallel with the bed of the machine are designated 60 and 61 for the lower jaws and 62 and 63 for the upper set of jaws. The jaws 60 and 62 are pivoted on the bolt 65 while jaws 61 and 63 are pivoted on the bolt 66. Springs 67, one for each jaw, tend to move the working ends of the jaws apart, while wedges operate to move the jaws about their pivot into gripping relation. The lower set of jaws 60 and 61 are operated by a slide block 70, shown in dotted lines in Fig. 1, having a wedge-shaped piece 71 fitted into the forward end thereof for engagement with the flaring ends of the jaws 60 and 61. This slide is operated by a cam 72 working through roll 73 and adjustable set screw 74 mounted on the raised block 75. The upper set of jaws 62 and 63 are operated by the cam 77 through roll 78, adjustable set screw 79, slide 80 and wedge-shaped end 81 to engage the slightly flaring ends 82 of the jaws 62 and 63.

This slide 80 is cut out to receive the raised block 75 projecting upwardly from the slide below. The forward end 83 of the jaw 62 slides across the notched L-shaped end of the member 56 and shears off the wire and carries this end of the wire forward as the other jaw operates to grip the link in a plane passing through the center of the jaws 62, 63 and the companion jaws, to be presently described.

Jaws 85 and 86 grip the other end of the link 10 and are mounted on a pivot 87 and within cylindrical member 88 having an enlarged head 89 with a slot as at 90 for the reception and guiding of these jaws in their pivotal mounting. This member 88 is cut to form a gear 91 and is also bored as at 92 for the reception of operating plunger 93 having a chisel-shaped end 94 for spreading the inner ends of the jaws 85 and 86 to close them onto the link at the desired time. This member 88 is rotatably mounted in a sliding head 96 which has dove-tailed engagement as at 97 with a vertically reciprocating carriage 98 which is vertically slidably mounted in the frame portion 99 secured to the bed of the machine. A rack 100 is slidably mounted in the head 96 and has its teeth engaging the teeth 91 of the member 88. A plate 101 on the end of rack 100 is engaged by a roller 102 on a lever 103 which projects through the bed and is secured to the rod 104 mounted in bearings 105 beneath the bed of the machine. At the other end of this rod there is another lever 106 extending up through slot 107 in the bed of the machine, which is provided with a roller 108 for engagement with the cam 109 on the cam shaft 21, which cam will swing the lever and rotate rod 104 to move the rack 100 inwardly and rotate the member 88. A collar 110 is fixed on the member 108 by means of the set screw 111, which set screw is provided with a pin 112 engaged by a spring 113 anchored to the bed of the machine as at 114 tending to return the member 88 and thus project the rack 100 in the opposite direction.

In order that the carriage 98 may be moved vertically or up and down with relation to the bed 20, I provide a lever 115 which is connected by means of set screws 117 and 118 extending through the bifurcated portion 120 of the lever and held in position by the check nuts 121 to a projection 116 on the lower portion of the carriage 98. This lever is pivoted beneath the bed of the machine intermediate its ends and is connected to a slide 125 positioned through the bed of the machine and suitably guided for vertical movement. On one side of this slide there is a roller 126 for engaging cam 127 to operate the slide in one direction, while on the other side of the slide 125 there is a roller shown dotted as at 128, and is similar to the roll 127, for engagement with the cam 129 to operate the slide in the other direction. Thus, as this slide moves up and down the lever is moved about its pivot to move the carriage 98 vertically through substantially one-half an inch to vary the position of the jaws 85 and 86 in the operation of the machine.

The sliding head 96 is forced in one direction by means of springs 130 guided on rods 131 and acting between the abutment 132 and carried by the carriage 98 and the abutment 133 on the head 96.

Collar 135 threadingly engages the reduced portion 136 on the end of the member 88 and is engaged by the roll 137 on lever 138 which is pivoted as at 139 for moving the head 96 forwardly. This lever 138 is operated from cam shaft by cam 140.

through the rod 142 having a roll 143 which is drawn into engagement with the cam by spring 144 and having a threadingly adjustable portion 145 held in position by the check nut 146 for engaging the lever 138 and moving it about the pivot 139, whereby the jaws are positioned the proper amount forwardly for gripping the link. In order to close the jaws 85, 86 a lever 150 pivoted as at 151 and provided with a roll 152 engaging the enlarged end 153 of the plunger 93 is moved by means of cam 154 on the cam shaft through rod 155 having a roll 156 held in engagement with the cam by spring 157, there being an adjustable end portion 158 to contact the lever 150, the adjustment being maintained by the check nut 159. As the plunger 93 is moved inwardly the jaws 85, 86 move to gripping position and the springs 130 are somewhat compressed. After the jaws are moved to gripping position and rotation of the jaws occurs, there is a shortening of the link due to its twisting, and as this occurs, the lever 150 is given a further movement by means of the cam 161 acting through the rod 162 having cam roll 163 which is held in engagement with the cam through spring 164. This rod 162 has mounted thereon a block 165 carrying a threaded pin 166 to engage the block 167 fixed on the rod 155 by set screw 168 to pick up the rod 155 and carry it forward in an amount sufficient to take up the fore-shortening of the link by reason of its twist and at the same time maintain the jaws in firm gripping relation on the link. This threaded member 166 may be maintained in adjusted position in the block 165 and held there by the check nut 169, thereby enabling fine adjustments to be had.

This machine is designed primarily for making curb chain, and in order that each link may pass through two previously formed links and make what is known as a double curbed chain, I have provided a probe 175 which is mounted at the end of a lever 176 pivoted as at 177 and having an L-shaped arm 178 engaging a cam 179 which is mounted upon the mandrel 41. This probe 175 operates through a guide bracket 180 which is suitably mounted upon some fixed part of the machine. There is also a holding member 181 which is mounted upon lever arm 182 pivoted as at 177 and having an L-shaped arm 183 engaging the cam 184 turning with the mandrel 41. This holding member will move down into engagement with the previously formed links to move them out of the way of the jaws just prior to these jaws gripping the link, and the probe descends to force the links into a position so that the opening through the links will be in proper registry for the passing through two previous links of the wire for the formation of the next link. This holding member is L-shaped with a foot portion 185 and secured to its lever 182 by the screw 186 at an angle to permit some resiliency or spring of the stock.

In some cases it is desirable to provide a lateral movement of the probe as well as a downward vertical movement thereof; and in order to accomplish this result I provide a guide 200 with a sliding member 201 located therein having a spring 202 attached to this member and tending to move the same upwardly after being forced down by the lever 176, this spring being attached as at 203 to some convenient stationary part of the machine and merely passed through an opening 204 in the slide member 201. The probe, designated 205, is of an L-shaped formation and is pivoted as at 206 to the slide 201 with a spring

207 encircling the pivot 206 and extending through an opening 208 in the arm 209 of this probe. A pin 210 is located on the guide and as the slide member 201 descends with the probe 205 this laterally extending arm 209 strikes the pin 5 210 and further movement downwardly by the slide 201 causes a lateral movement of the probe 205, as indicated in Fig. 18, so as to move the previously formed link 191 to one end of the gripped link 190 for the insertion of the wire 192, 10 as shown in Fig. 18.

This machine may be very readily adapted to make links other than those specified heretofore. For instance, the cylindrical member 50 may be interchanged with a cylindrical member which 15 will form a link of a different size or shape and where I desire that a link pass through more than two previously formed links this cylindrical member will be made larger such as I have illustrated in Fig. 21, the cylindrical member now 20 being designated 215, and in this showing in order that the wire 216 may pass through three links as 217, 218 and 219, I provide for the jaws 85 and 86 to hold the link 217 slightly further to the left than that of the previous description, 25 see for instance Fig. 13, and I also adjust the probe 175 slightly to the position illustrated in Fig. 21 so that it will cause the three links to be crowded over to allow room for the wire 216 to be inserted. It thus will be apparent that various 30 different chains may be formed from the machine and the wire may be of various different shapes to acquire the desired design. As indicated, the wire may be passed through more than three links and so on, as desired, but the 35 longer the links are made to accommodate such passing through of several links the less flexible the chain will be, and accordingly, the flexibility desired will limit the plural structure of the chain in this manner. 40

In Fig. 21 I have also illustrated an L-shaped guide 220 which serves to cause the length of chain as it is formed to be dropped over this guide and maintain a desired relation with reference to the formed chain, this guide having been absent 45 from the other showings but is of a known conventional form.

Operation

The operation upon the wire of the machine 50 can perhaps best be followed from Figs. 11 to 14 inclusive. The wire 53 is fed through the holder 211 into the grooved cylindrical member 59 and advanced by intermittent rotation of the mandrel. The mandrel is turned one complete revolution feeding the wire forward something after the form of a corkscrew, as may be seen from Fig. 11, which illustrates the link 190 just being formed and moved by the top jaws 62 and 63 and also gripped by the jaws 85 and 86. When the link is in this position the jaws 62 and 63 which have moved the ends of the link into alignment disengage the link, moving to the position shown in Fig. 12, and at the same time the carriage 98 is lowered so that the link is in a position to be gripped by the jaws 60 and 61 which next occurs, as shown in Fig. 12. When the jaws 60 and 61 engage the link the jaws 85 and 86 are given a rotation through 90° by reason of the movement of the rack 100 operated through its 70 cam and at the same time the jaws 86 are moved inwardly so as to take up the shortening of the length of the link due to the twisting as above explained. After this action has occurred, the jaws 60 and 61 open to release the link 190 and 75

the jaws 85, 86 are given a portion of a turn substantially 45°, shown in Fig. 13, where, due to the suitable dwell of the cam operating these jaws, they are held and while in this position 5 the worm starts to feed the wire and immediately the probe 175 or 205 descends at a rapid rate overtaking the end of the wire and moving the previously formed link 191 out of the way to provide a space for the reception of the wire for the 10 next link through these two previously formed links, as shown in Fig. 13; in the meantime, the mandrel 41 is rotated to feed the wire 192 through the formed opening and this wire also pushes the previous link a little to one side and 15 to the position illustrated in Fig. 14, the probe is then withdrawn, after which the jaws 85 and 86 release the link 190 permitting it to drop to the position such as illustrated in Fig. 14, previous to the severance of the wire, and then these 20 jaws are drawn away from the link by movement of the head 97 and are rotated through another 45°. During this movement of the jaws 85, 86 the presser 181 descends to move these previously formed links to the bottom of the arc 25 of the wire 192 and out of the way of the jaws 85, 86 when they next advance by a movement of the head 97 so as to grip the wire at 193 just prior to its severance, and after so gripped the jaw 62 operates, which, in cooperation with the 30 portion 57 of the member 56, severs the wire and continuing movement of the jaws 62 and 63 force the ends of the link into aligned relation, and the link is thus then arranged as shown in Fig. 11, except that as shown in Fig. 14 there are 35 additional links formed after the above-described cycle of operations, whereupon the machine repeats this cycle forming a chain automatically of indefinite length. In this manner, a double, triple or the like curbed chain is formed 40 automatically without the use of solder, an essential portion of the machine for rapid operation being the guides and holding device which positively position the previous formed links such that the wire may feed therethrough in the desired manner.

The foregoing description is directed solely towards the construction illustrated, but I desire it to be understood that I reserve the privilege of resorting to all the mechanical changes to 50 which the device is susceptible, the invention being defined and limited only by the terms of the appended claims.

I claim:

1. In a chain machine, mechanism for forming 55 curbed chain links including means for holding the last formed link for the insertion of wire therethrough, probing means having a portion insertable in the previously formed link and operating to positively position said previously 60 formed link for the reception of said wire for the next link therethrough, whereby two previously formed links are embraced by each link as formed, and means to effect a longitudinal and also a lateral movement of said probing means 65 for positioning the previously formed link.

2. In a chain machine, mechanism for forming curbed chain links including means for holding the last formed link for the insertion of wire therethrough, probing means operating to positively 70 position the previously formed link for the reception of said wire for the next link therethrough, whereby two previously formed links are embraced by each link as formed, and a presser foot engaging the previously formed link 75 and positively moving it to a desired position.

3. In a chain machine, means for shaping wire in generally the shape of a helix and feeding the same forward in a corkscrew manner, means for forming links therefrom, means for curbing each link as formed, means for moving the last formed link for the reception of the helical wire as fed forward, and a probe to pass through said last formed link and the next previously formed link to provide for the reception of the helical wire as fed forward. 10

4. In a chain machine, means for shaping wire in generally the shape of a helix and feeding the same forward in a corkscrew manner, means for forming links therefrom, means for moving the last formed link for the reception of the wire as fed forward, means for positioning the next previously formed link to also receive the wire as fed forward, and a presser foot to assist in moving the previously formed links to a given position. 15

5. In a chain machine, means for shaping wire 20 in generally the shape of a helix and feeding the same forward in a corkscrew manner, means for severing a convolution of the wire and bringing its ends together to form a link, means for gripping and twisting the link, means for moving the last said gripping means to position its link to receive the wire as fed forward, and means for positioning the next previously formed link to receive said wire as fed forward. 25

6. In a chain machine, means for shaping wire 30 in generally the shape of a helix and feeding the same forward in a corkscrew manner, means for severing a convolution of the wire and bringing its ends together to form a link, means for gripping and twisting the link, means for moving the last said gripping means to position its link to receive the wire as fed forward, means for positioning the next previously formed link to receive said wire as fed forward. 35

7. In a chain machine, means for shaping a length of wire in generally the shape of a helix and feeding the same forward in a corkscrew manner, means for severing a convolution of the wire and bringing its ends together to form a link, means for gripping and twisting the link, means for moving the last said gripping means to position the link to receive the wire as fed forward, and a probe to pass through the gripped link and the next previous link and provide an opening for the reception of said wire. 45

8. In a chain machine, means for shaping wire in generally the shape of a helix and feeding the same forward in a corkscrew manner, means for severing a convolution of the wire and bringing its ends together to form a link, means for gripping and twisting the link, means for moving the last said gripping means to position the link to receive the wire as fed forward, and a probe to pass through the gripped link and the next previous link to provide an opening for said wire and move the other links to one side. 55

9. In a chain machine, means for shaping wire in generally the shape of a helix and feeding the same forward in a corkscrew manner, means for severing a convolution of the wire and bringing its ends together to form a link, means for gripping and twisting the link, means for moving the last said gripping means to position the link held thereby to receive the wire as fed forward, a probe to pass through the gripped link and the next previous link and provide an opening for the reception of said wire, and a presser foot for moving the previously formed links to a predeter- 70

mined position just prior to the first grip of the jaws on said wire.

5. 10. In a chain machine, means for forming curbing and holding a link, means for shaping wire in generally the shape of a helix and feeding the same forward in a corkscrew manner through the two links previously formed, means

causing said holding means to drop the last formed link through which the wire is threaded prior to severing and obtain a new grip on the wire just fed, and a power actuated presser foot to assist the dropped links in moving to desired 5 position.

WILLIAM F. BIEDERMANN.
